UNITED STATES PATENT OFFICE.

HENRY M. SHEER, OF QUINCY, ILLINOIS.

KNOCKDOWN BROODER-CANOPY.

1,392,708.

Specification of Letters Patent.

Patented Oct. 4, 1921.

Application filed May 14, 1920. Serial No. 381,320.

To all whom it may concern:

Be it known that I, HENRY M. SHEER, a citizen of the United States, residing at Quincy, in the county of Adams and State 5 of Illinois, have invented certain new and useful Improvements in Knockdown Brooder-Canopies, of which the following is a specification.

My invention relates to an improvement 10 in knockdown brooder canopies.

My construction provides a canopy which is the equal for all practical purposes of the modern type of canopy that is assembled complete in every way at the factory and 15 shipped out in that form. But there are objections to such canopies, because canopies which are fully assembled at the factory and then crated or shipped necessarily occupy a great deal of room, and dealers 20 object to this because of the space required to accommodate them in their warehouses; and, furthermore, if any part is damaged, it means the entire canopy, whereas with the construction which I have devised in 25 case of damage to one or more sections, these sections are capable of being replaced by the user without the damage or loss of the entire canopy.

With my form of brooder canopy, there 30 may be two or more sections, and these are capable of being closely nested and compactly packed for shipping and storage, and they are so constructed that the user can easily assemble the parts, or take it apart 35 at will, should occasion require.

My present invention is, therefore, a canopy composed of two or more sheet-metal sections, the edges of which are provided with interlocking seams adapted to 40 fit together, and these are so offset that the upper surface of the sections is substantially flush when the parts are assembled, and by bolting through the seams and providing braces, a substantial brooder canopy 45 of the knockdown type is provided.

Another feature is a damper at the apex, which is both easily adjustable and removable. Another feature is a suspensory arrangement for a thermometer, which can be 50 easily lifted out of the brooder and examined. Still another feature comprises the removable legs.

In the accompanying drawings:

Figure 1 is a view in perspective;

Fig. 2 is a view of one of the sections;

Fig. 3 is a vertical transverse section;

Figs. 4 and 5 are details;

Fig. 5^a is an enlarged fragmentary sectional view through the top of the canopy.

Fig. 6 is a view showing a rectangular 60 diaphragm in lieu of the braces.

While the brooder canopy may be made of any number of sections, in the construction shown there are four of these sections, designated by the numeral 1. These are all 65

alike, and they are cut and mitered or interlocked as at 2 and 3, so they will fit together and form the complete canopy when assembled, and these mitered edges 2 and 3 are preferably offset to provide a substantially flush upper or outer surface. The sections are held together by bolting through the mitered or interlocking edges 2 and 3, as shown at 4. An opening 5 is formed at the apex, and a cast-iron ring 75 6 with a collar 7 is fitted to and dropped down into this opening 5; by reason of the sections being flush, it fits tightly, as shown in Fig. 5^a, without the necessity of forming notches and clearance spaces. This ring is 80 preferably held in place by the upper set of bolts which holds the sections of the canopy together. The lower end of the ring has an annular inwardly-extending flange 8, forming an opening 9 and constituting a seat 85

for the damper. The damper comprises two disks 10 and 11 having registering holes 12 and 13 therein, respectively, and these disks are pivoted together by a rivet 14 at the center, so that the upper and smaller 90 disk 10 is rotatably mounted on the lower larger disk 11, which constitutes its support. A handle 15 is loosely connected with the upper rotatable disk 10 as a means for turning the disk and regulating the size of 95

the registering openings 12 and 13, or closing them altogether, or as a means for removing the damper when desired to look into the brooder canopy from the top to observe the condition of the burner from 100 beneath.

To give strength to the canopy, the outer edges of the sections are crimped or corrugated as at 16, and braces 17, one for each section, are provided, having their ends held by the bolts 4 at the seams, thus giving 105 rigidity and strength to the canopy.

The canopy is mounted on legs of any approved construction, as for instance made of wire 18 being as shown in Fig. 5, and held 110 in place by a clip 19 and the bolts 4.

A thermometer 21 is adapted to be

dropped through a hole 22 provided therefor and held by a rod 23, which slides loosely through a disk 24, which closes the hole and supports the thermometer when the latter is lowered. A loop 25 at the top of the rod 23 constitutes a handle and a means for raising and lowering the thermometer when it is to be examined.

Thus I have provided a simple form of brooder, which can be produced economically and is capable of being easily knocked down or set up, compactly packed, shipped and stored, and it requires no special skill to set it up. At the same time, the device is light and strong, and the ventilation can be easily and quickly regulated and the interior inspected without the slightest inconvenience.

In lieu of the braces, the rectangular dia-
20 phragm 27, shown in Fig. 6, is secured at its four corners by seam securing bolts. The opening 28 at the center is to receive the burner (not shown). The diaphragm serves two functions, namely of the braces, and also 25 increases the heat radiating surface of the canopy.

I claim:

1. A knockdown canopy including sections mitered and interlocked at their edges 30 and made substantially flush on their outer surfaces, the canopy thus formed having an opening at the apex, a ring fitted to and dropped into said opening and substantially fitting the surrounding outer surface, and 35 forming a seat at its inner end, and a damper removably supported on said seat.

2. A knockdown canopy including sections mitered and interlocked at their edges and made substantially flush on their outer 40 surfaces, the canopy thus formed having an opening at the apex, a ring fitted to and dropped into said opening and substantially fitting the surrounding outer surface, and forming a seat on its inner end, and a 45 damper removably supported on said seat, said damper composed of two perforated rotatably connected disks and a handle for regulating and removing the same.

3. A knock-down canopy for brooders and 50 the like, including a plurality of fan-shaped

sections, the side edges of which are interlocked and detachably bolted through, and rigid bracing means extending horizontally within the canopy and secured to each fan-shaped section, the canopy and bracing 55 means being open through the center, and means for controlling the outlet of air through the openings in the canopy.

4. A knock-down canopy including a plurality of similarly formed fan-shaped sections crimped only at their outer edges to give them rigidity, means for securing said sections together at their side edges to form a complete canopy, a damper at the apex, means at the bottom for holding the canopy 60 a suitable distance above the ground or floor, and bracing means within the canopy extending horizontally, and detachably connected therewith.

5. A knock-down canopy including a plurality of fan-shaped sections detachably interlocked together at their side edges and having a central opening at the apex when together, a ring having a collar fitted to and dropped down into this opening, said 70 collar having an inwardly extending flange and a damper comprising two disks pivoted together and having registering holes adapted to be seated on the flange for regulating the draft through the opening. 80

6. The combination with a knockdown canopy made of mitered interlocking sections having an opening at the top and braces extending to the joints between the sections, of a ring secured in the opening, and a 85 damper adjustably and removably supported in the ring.

7. The combination with a knockdown canopy made of mitered interlocking sections having an opening at the top and braces 90 extending to the joints between the sections, of a ring secured in the opening, a damper adjustably and removably supported in the ring, legs, clips embracing the legs, and bolts for securing the mitered interlocking edges 95 of the sections together, certain of said bolts utilized for holding the ring, the ends of the braces and the clips for the legs in place.

In testimony whereof I affix my signature.
HENRY M. SHEER.
